COMBINED DISPLAY SIGN AND CLOCK

Anthony Rand, 7 SE. Dunham, Des Moines, Iowa

Filed Dec. 11, 1963, Ser. No. 77,747

Term of patent 7 years

(Cl. D1—12)

Fig. 1

Fig. 2

FIG. 1 is a front perspective view of a combined display sign and clock showing my new design; and FIG. 2 is a rear perspective view thereof.

I claim:

The ornamental design for a combined display sign and clock, as shown.
